UNITED STATES PATENT OFFICE.

PARKE T. SNYDER, OF CHICAGO, ILLINOIS, ASSIGNOR OF ONE-HALF TO ROSS J. BEATTY, OF CHICAGO, ILLINOIS.

FLUME.

1,102,810.

Specification of Letters Patent.

Patented July 7, 1914.

Application filed August 11, 1913. Serial No. 784,106.

To all whom it may concern:

Be it known that I, PARKE T. SNYDER, a citizen of the United States, residing at Chicago, in the county of Cook and State 5 of Illinois, have invented certain new and useful Improvements in Flumes, of which the following is a specification.

My invention relates to improvements in metallic flumes.

10 One of the objects of my invention is to provide a flume that can readily and quickly be made or built up of a series of sheets of metal, each sheet constituting a section whose longitudinal sides practically meet, 15 thereby providing a flume that is substantially a complete cylinder, in so far as its functions as an open flume are concerned.

In a copending application for flumes, filed by me March 31, 1913, and identified 20 by Serial No. 757,733, I have disclosed a similar structure made of a series of sheets of metal interlapped at adjacent edges to form a joint and secured at the side marginal edges of the lap, at equal distances apart 25 for each sheet, as when the sheets are laid flat, and subsequently bowed into trough like shape, whereby the lapped surfaces are brought into very intimate contact by thus subjecting the outer sheet to expansion stress 30 and the inner sheet to compression stress as the result of the manner of their attachment and the subsequent bowing of the sheets.

My present invention utilizes the same 35 general manner of attachment of the adjacent sheets to form the joint therebetween but employs a more specific means of carrying the joining operation into effect.

It furthermore comprises novel and useful means for mutually holding the marginal, longitudinal edges of the structure in 40 position, to provide a flume of more nearly cylindrical cross section.

In the accompanying drawings forming a 45 part hereof:—Figure 1 is a plan view of a portion of the completed flume. Fig. 2 is a transverse section, taken on line 2—2 of Fig. 1. Fig. 3 is an enlarged, fragmentary section, taken on line 3—3 of Fig. 1. Fig. 4 is a similar section of a modification.

50 In all the views the same reference characters are employed to indicate similar parts.

The flume is made of a series of sheets of 55 suitable metal, such as 5 and 6, preferably tapered in width slightly, so that the adjacent ends, of sheet 5, when properly formed,

may enter into the formed end of sheet 6, in interlapped relation to form a joint.

In Fig. 3 the longitudinal marginal edges of the outer sheet are turned back upon themselves to form a holding means for the 60 adjacent inner sheet. When the sheets are thus formed at their marginal edges, sheet 6 is telescoped within this portion of sheet 5, so that when the structure is bowed, or curved into substantially circular formation, 65 as shown in Figs. 1 and 2, there is no relative circumferential shifting or movement of the sheets, and therefore the outer sheet 5 is subjected to considerable expansion strain and the inner sheet 6 is subjected 70 to considerable compression strain, the result of which is that their contacting surfaces at the joints are forcibly pressed together thereby making a completely, watertight joint. This is substantially 75 the method of making the joints described and claimed in my former application, but the means of utilizing these folded marginal edges for the purpose of mutually holding the structure in trough like, or cylindrical form, was not contemplated in my 80 former application.

Fig. 3 shows the interlapped relation at the joint of the two sheets wherein a transversely disposed clip 7 having its ends 85 turned back upon themselves, as at 8, is inserted between the lapped portions of the inner sheet 6, to hold the sheet in substantially cylindrical form. The substantial equivalent of this means of mutually holding the edges of the structure together is 90 shown in Fig. 4, wherein sheets 5 and 6, on one of the marginal edges, are bent back upon themselves and occupy the same relation as the same sheets are shown to occupy 95 on both sides, in Fig. 3, but on the other side of the marginal edge, sheet 6 is bent back over the end 5' of sheet 5, as at 6', and the lapped portions of sheets 5 and 6, on the one side, are inserted between the 100 terminals 5' 6' of the other side and the body of said other side, thereby mutually holding the longitudinal edges of the structure together without the necessity of employing a clip, such as indicated by 7. The 105 folds of the longitudinal marginal edges of the modified structure, shown in Fig. 4, will operate to produce the same compressing and expanding effects of the respective sheets at the joints, as shown in Fig. 3. 110

When arrangement of joining the edges together, as shown in Fig. 4, is continued between the joints it forms a practically closed structure.

5 One of the advantages of a closed, or substantially closed, structure is to prevent limbs, leaves of trees, and other debris from falling into the flume and it furthermore increases the capacity of the flume and prevents evaporation to some extent.

10 The folds of the longitudinal marginal edges of the respective sheets may be made by use of proper apparatus on the ground upon which the flume is to be erected so that the sheets may be shipped from the factory in a perfectly flat state, in which condition they will occupy minimum space. The structure thereafter may be readily and quickly put together upon the ground, without 15 the necessity of special tools, and it may be supported by any means usually employed for the support of similar pipe structures.

20 After the sheets have been folded at their longitudinal, marginal edges, and one sheet telescoped within the other and the structure bowed into trough or cylinder like shape it is practically impossible to pull the sheets apart as the compression and 25 expansion strains are so great that the friction effected thereby practically holds the sheets against displacement under any ordinary condition of use.

30 While the cleat 7 is shown to be relatively short it is evident that it may extend substantially the full length of the sheets

and thereby substantially close the opening between the opposite longitudinal edges of the sheet.

40 While I have herein shown a single embodiment of my invention for purpose of clear disclosure it is evident that departure may be made from the specific showing within the scope of the appended claims.

Having described my invention, what I 45 claim is:—

1. A flume comprising a series of sheets interlapped at their ends, having their longitudinal edges folded upon themselves and bowed into cylindrical form, and connected, 50 to mutually hold the structure in shape.

2. A flume comprising a series of sheets, each having its longitudinal edges folded back upon itself, the ends of adjacent sheets interlapped, one within the other, to provide joints therebetween, and bowed into cylindrical shape, and means for connecting the longitudinal edges to mutually hold the structure in shape.

3. A flume comprising a series of sheets, 60 each having its longitudinal edges folded back upon itself, the ends of adjacent sheets interlapped one within the other to provide joints therebetween, and bowed into cylindrical shape, and cleats engaging the folded 65 edges to hold the structure in shape.

In testimony whereof I hereunto set my hand in the presence of two witnesses.

PARKE T. SNYDER.
